LEG SUPPORT FOR FOLDING CARD TABLES

Eugene C. Turner, San Diego, Calif.

Application December 14, 1931
Serial No. 530,945

7 Claims. (Cl. 45—11)

My invention relates to leg supports for folding card tables, and the objects of my invention are:

First, to provide a device of this class which, although particularly adapted for folding tables, 5 may be used to form supports for legs of other articles of furniture, such as chairs, benches or the like;

Second, to provide a device of this class which facilitates the construction of a particularly 10 sturdy table yet permits the legs thereof to be folded readily and quickly;

Third, to provide a device of this class which is particularly easy to position accurately with respect to the table and be secured thereto, thus reducing the time and effort required in the 15 construction of the table;

Fourth, to provide a device of this class which braces the legs in all directions;

Fifth, to provide a device of this class which 20 incorporates a novel folding brace means, and

Sixth, to provide on the whole a novelly constructed leg support for folding card table which is durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly 25 set forth in the appended claims, reference being had to the accompanying drawing and to the characters of reference thereon which form a part of this application, in which:

Figure 1 is a perspective view of my device with 30 adjacent parts and portions of the table shown fragmentarily and viewed from the underside thereof; Fig. 2 is an elevational view of one of the frame brace members; Fig. 3 is a similar 35 elevational view of a co-acting brace member; Fig. 4 is an enlarged fragmentary sectional view 40 through 4—4 of Fig. 1 with the table structure omitted; Fig. 5 is a similar enlarged sectional view 45 through 5—5 of Fig. 8; Fig. 6 is another fragmentary sectional view through 6—6 of Fig. 8; Fig. 7 is still another fragmentary sectional view 50 through 7—7 of Fig. 8, and Fig. 8 is a reduced bottom view of my device with the leg in its folded 55 position.

Similar characters of reference refer to similar 60 parts and portions throughout the several views of the drawing.

Corner plate 1, screws 2, hinge pin 3, leg bracket 4, screws or bolts 5, brace member 6, pivot pin 7, 65 sliding pin 8, locking plate 9, and spring 10, constitute the principal parts and portions of my novel leg support for folding card tables.

The table T for which my device is particularly 70 adapted is provided with a depending marginal rim T1. Four of the leg supports are used to each 75 table, one in each corner. Each leg support in-

cludes a corner plate 1 having a flat substantially triangular portion 1a adapted to fit against the under side of the table top, and depending marginal walls 1b along two right-angularly disposed sides of the flat portion 1a. The walls 1b fit 80 against the marginal portions T1 of the table and when secured thereto by means of screws 2 hold the corner plate 1 in proper relation with the table.

The flat portion of the corner plate 1 is provided with a pair of downwardly extruded loop portions 1c which are arranged in axial alinement with each other and in parallel spaced apart relation with one of the depending walls 1b. One of the loop portions 1c is located contiguous to the 85 remaining wall 1b. This wall is provided with a recess 1d abutting said loop portion. A hinge pin 3 is supported by the loops 1c and one end thereof extends into the recess 1d.

The hinge pin 3 journals the loop portion 4a 90 of a leg bracket 4. Said leg bracket 4 is substantially triangular with its extended apex portion adjacent the right-angular corner of the corner plate 1. This portion of the leg bracket 4 is bent to form a rectangular loop or socket 4b which is 95 adapted to receive a leg L. The socket 4b is disposed on the side of the bracket towards the wall 1b which is parallel with the axis of said bracket. This arrangement enables the leg L to lay adjacent the under side of the table top 100 when in the folded position shown in Fig. 8. The loop or socket 4b is not closed but the margin of the bracket which completes the loop forms a flange 4c in spaced relation with the main portion of the bracket. Screws 5 extend through 105 the main portion of the bracket and said flange 4c so that the loop or socket may be contracted, thereby firmly holding the leg L. The leg bracket 4 braces the leg in the direction of the axis of the pin 3.

The leg is braced transversely to the axis of the hinge pin 3 by means of a collapsible brace structure. This structure includes a brace member 6, the one end of which is pivotally mounted upon a pivot pin 7 which extends from the wall portion 1b disposed at right angles to the hinge pin 3. The pivot pin 7 is supported from a boss portion 110 1e which is extruded from said wall 1b. The brace member 6 is provided with a longitudinally extending slot 6a therein which is disposed in slightly downwardly offset relation with its longitudinal axis, as viewed in Fig. 1. The extended portion of the slot 6a is turned upwardly, as indicated by 6b, forming a catch portion. The end of the slot 6a adjacent the pivoted portion of the brace member is enlarged slightly so 115 as to receive the head of a sliding pin 8. The sliding pin 8 is adapted to shift along the slot 6a and fit in the catch portion 6b. Said pin is supported from an extruded boss portion 4d extend- 120

ing from a wall of the socket 4b of the leg bracket 4, as shown best in Fig. 6.

Intermediate its ends the brace member 6 is U-shape, as indicated by 6c. Pivoted on the same axis as the brace member 6 is a locking plate 9 which is adapted to fit between the walls of the U-shaped portion 6c of the brace member and is provided with a longitudinally extending slot 9a corresponding to the slot 6a; said slot 9a being adapted to receive the sliding pin 8. Adjacent the pivoted end of the locking plate, said locking plate is provided with a hook portion 9b which is adapted to retain one end portion of a spring 10 which is wound around the boss portion 1d and the other end thereof inserted into the U-shaped portion 6c of the brace member so as to engage the cross portions thereof. A spring so positioned tends to spread the extended ends of the brace member and locking plate outwardly from each other. This tendency causes the pin 8 to assume automatically an interlocked position in the catch portion 6b when the leg is shifted to its upright position shown in Fig. 1. Upward pressure upon the brace member 6 against the action of the spring 10 releases the pin 8 so that it may slide along the slot 6a, thereby enabling the leg to move to its folded position, shown in Fig. 8. In this position the brace structure is disposed along the side of the leg between said leg and the wall 1b.

The side of the corner plate opposite from the walls 1b is provided with a downwardly offset projection 1f which is adapted to be secured to one end of a brace member B disposed adjacent the table top T.

Once the table top T and marginal rim T1 is constructed it is an extremely simple matter to position the assembled leg supports in the four corners of the table. No measurement or adjustment is needed; the corner plates form their own templates.

With reference to the dotted line view of the brace member or locking plate 9 shown in Fig. 2, it will be noted that the sliding pin 8 bears against the extended end of the slot 9a so that the locking plate 9 carries the tensile strains. The brace member 6 carries the compression strains by reason of the inward wall of the catch portion or notch 6b. This wall tapers outwardly slightly from a true arc so that as the slot 9a and notch 6b wears the pin moves deeper, that is, towards the extremity of said notch 6b.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a furniture leg supporting unit, a corner plate including a flat portion with a pair of right-angularly disposed marginal portions, depending walls extending along said marginal portions, and an offset brace receiving means disposed along the remaining side of said corner plate, a bracket hinged to said corner plate, a leg receiving means

disposed at one extremity of said bracket, the remaining portion of said bracket forming a brace therefor, and a collapsible brace extending from said plate to said leg receiving means in angular relation with the hinged axis of said bracket.

80

2. In a furniture leg supporting unit, a substantially triangular corner plate including a flat portion, depending marginal walls along two sides of said plate and an offset brace receiving means disposed at the third side of said flat portion, a furniture leg receiving bracket hinged to said corner plate, and a collapsible brace means arranged to secure said bracket in its extended position.

85

3. In a furniture leg supporting unit, a corner plate, hinge elements formed integrally therewith, a bracket including hinge means arranged to coact with said hinge elements, a furniture leg receiving socket disposed along one margin of said bracket, and means associated with said socket for clamping a furniture leg therein, the remainder of said bracket forming a brace for said socket, and a collapsible brace means arranged to secure said bracket in its extended position.

90

4. In a device of the class described, a hinged furniture leg, and a collapsible brace structure therefor including, a pair of brace elements pivotally supported about a common axis, and yieldable means tending to spread the extended ends of said brace elements, said brace elements provided with longitudinally extending slots, and a means on said furniture leg slidable in said slots.

95

5. In a device of the class described, a hinged furniture leg, a rotatable brace element provided with a longitudinally disposed slot therein, including a catch notch at one extremity, means on said leg slidable in said slot, and yieldable means associated with the pivoted end of said brace element and extending therewith tending to force said slidable means into said catch notch.

100

6. In a furniture leg supporting unit, a furniture leg receiving socket, a bracing fin forming an extension of a side of said socket, a hinge element disposed along a margin of said fin, a corner plate, hinge means associated therewith arranged to coact with said hinge element, a collapsible brace structure disposed in angular relation to said hinge means including a pair of brace elements pivotally supported from said corner plate about a common axis, and yieldable means tending to spread the extended ends of said brace elements, said brace elements provided with longitudinally extending slots, and a pin associated with said socket slidable in said slots.

105

7. In a furniture leg supporting unit, a furniture leg receiving socket, a bracing fin forming an extension of a side of said socket, a hinge element disposed along a margin of said fin, a corner plate, hinge means associated therewith arranged to coact with said hinge element, a brace member pivotally connected with said corner plate and extending in angular disposed relation to said hinge means, a longitudinally extending guide means formed by said brace member including a catch portion at the extremity of said brace member, a pin on said socket shiftable along said guide means, and yieldable means associated with said guide means tending to force said pin in said catch portion.
